[57] CLAIM

The ornamental design for combined clock & multi-image picture frame, as shown and described.

DESCRIPTION

FIG. 1 is a front elevational view of the first embodiment of the combined clock and multi-image picture frame of this design;

FIG. 2 is a right side elevational view thereof. The left side view would be a mirror image;

FIG. 3 is a rear elevational view of this embodiment;

FIG. 4 is a bottom plan view thereof;

FIG. 5 is a top plan view thereof;

FIG. 6 is a top and right-front perspective view thereof; and,

FIG. 7 is a front elevational view of FIG. 1 in an inverted position.

The broken-line disclosure of FIGS. 1, 6-7 is environmental only and forms no part of the claimed design.

FIG. 1FIG. 3

FIG. 4

FIG. 5

FIG. 6

FIG. 7
